Term of patent 7 years

(Cl. D55—1)

To all whom it may concern:

Be it known that I, Marion R. Frazier, Jr., a citizen of the United States, residing at Delawanna, in the county of Passaic and State of New Jersey, have invented a new, original and ornamental Design for Combined Bracket and Gear Case for Package Filling Machines, of which the following is a specification, reference being had to the accompanying drawing, forming part thereof.

Fig. 1 is a perspective view of a combined bracket and gear case for package filling machines, showing my new design.

Fig. 2 is a bottom plan view of the same.

Fig. 3 is a side elevational view of the combined bracket and gear case, looking toward the side not disclosed in Fig. 1.

I claim:

The ornamental design for a combined bracket and gear case for package filling machines, as shown.

MARION R. FRAZIER, JR.
